UNITED STATES PATENT OFFICE

HUGH MOORE, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA

DISPENSING DEVICE

Application filed May 24, 1926. Serial No. 111,259.

This invention relates to improvements in dispensing devices and more particularly to dispensing devices of the type comprising a supporting member or holder having means providing for delivering or removing articles singly from a stack, and a removable container of tube like form for articles to be dispensed, the supporting member or holder having a socket part to receive and hold the removable container.

In dispensing devices of the class referred to, the tube like container may take the form of a tube of circular cross section, or a tube or paper carton square shape in cross section might be employed.

The object of the present invention is to provide an improved dispensing device of the general character referred to, to provide an improved supporting member or holder that is adapted to accommodate, without structural change, tube like containers of either circular or square cross section and whereby the same supporting member or holder is adapted to be used with removable containers of round and of square cross sectional form.

The invention, with other objects and advantages thereof, and the particular construction, combination and arrangement of parts comprising the same will be understood from the hereinafter contained detail description when considered in connection with the accompanying drawings, forming part hereof, and illustrating one embodiment of the invention.

In the drawings:

Figure 1 is a front elevation of a dispensing device having a supporting member or holder constructed in accordance with the present invention, a container tube of circular cross section being shown associated with the supporting member or holder.

Fig. 2 is a horizontal section on the line 2-2 of Figure 1.

Fig. 3 is a horizontal section on the line 3-3 of Figure 1.

Fig. 4 is a front elevation of the supporting member or holder with a container tube of square cross section associated therewith.

Fig. 5 is a horizontal section on the line 5-5 of Figure 4.

Fig. 6 is a vertical section.

The invention comprehends an improved supporting member or holder provided with a socket part comprising wall portions with similarly transversely curved inner faces disposed at different points about and extending in a common circle corresponding to the cross sectional size and curvature of a container tube of circular cross section, and spaced apart circumferentially to accommodate between the same the corner portions of a container tube of square cross section while having a supporting engagement with the flat faces thereof. More particularly the invention contemplates a socket structure of this character in which said wall portions having the curved inner faces are arranged in opposing relation at diametrically opposite points and in the combination with said wall portions of right angular shaped wall portions disposed intermediate the same and lying exteriorly of the common circle of the curved faces of said first mentioned wall portions.

Dispensing devices of the general type referred to comprising a supporting member or holder and a removable container tube are especially adapted for dispensing paper cups, and in the drawings, the invention is shown applied to a form of dispenser designed for this purpose.

Referring to a detailed description of the particular embodiment of the invention illustrated in the drawings, the supporting member or holder is in the form of a tubular part or casing of metal having associated therewith yieldable cup retaining means, and provided with an upper socket part to receive an end portion of and to support a container tube for a stack of cups. A designates the upper socket part and B is a depending skirt portion.

The socket part A comprises wall portions 1, 2, 3, 4, having similarly transversely curved or arcuate inner faces 1^a, 2^a, 3^a, 4^a, extending in a common circle corresponding to the cross sectional size and curvature of a container tube of circular cross section. The curved face portions 1^a, 2^a, 3^a, 4^a, of the wall

portions 1, 2, 3, 4 are of a width and equally spaced apart about the circle to accommodate between the same the corner portions of a container tube of square cross section while 5 having a supporting engagement with the flat faces thereof intermediate its corner portions, said socket part A being adapted to receive and hold container tubes of round and square cross sectional shapes as shown respectively in Figures 1, 2, 3, and Figures 4, 10 5, 6. In Figures 1, 2, 3, 5 designates a container tube of glass, in this instance, the arcuate face portions 1^a, 2^a, 3^a, 4^a throughout the same, fitting against the curved outer face 15 of the container tube. In Figures 4, 5 and 6, the container tube 6' takes the form of a paper carton, the same being engaged at its sides and supporting by the marginal edges of the arcuate face portions 1^a, 2^a, 3^a, 4^a, with 20 the corner portions of the carton disposed therebetween. In addition to the wall portions 1, 2, 3, 4, the socket portion is shown with right angular shaped portions 6, 7, 8, 9, extending between and exteriorly of the circle 25 of the arcuate face portions 1^a, 2^a, 3^a, 4^a, said right angular shaped wall portions joining the first mentioned wall portions, and, when a container tube of square cross section is seated in the holder, fitting against the corner 30 portions thereof and cooperating with the arcuate face portions 1^a, 2^a, 3^a, 4^a, to support the container tube.

In the particular construction shown, the front and side wall portions 1, 2, 3, of the 35 socket part A not only have inner curved faces but these complete walls have an arcuate bend, the socket being of general square shape form. The outer face 10 of the rear wall 4 of the socket is flat, as shown, to fit 40 against and be secured to any suitable support by screws 11, said rear wall being provided with screw apertures 12, the front wall of the socket having openings 13 located in alignment with the screw apertures 12 to accommodate the shaft of a tool in turning up 45 the screws.

Referring particularly to Figure 6 of the drawings, the particular cup retaining means shown, comprises resilient split ring members 14, 15 mounted in annular recesses or grooves 16, 17 in an annular carrier 18, which latter fits within the socket part A of the supporting member or holder and rests upon the inwardly extending bottom 19 thereof. 50 The split ring members 14, 15, are of an interior diameter slightly less than the greatest diameter of the cups a and adapted to engage the lowermost cup and support the stack of cups, and to expand sufficiently to permit 55 the withdrawal of the cups singly when a downward pull is exerted upon the lowermost cup.

By the special construction and arrangement of parts hereinbefore described, a cup 60 dispenser of a simple efficient nature is pro-

vided capable of being readily employed, without structural change, with container tubes of either round or square cross sectional form. The construction is of such a character as to provide an "efficient firm support for the container tube in either case, and at the same time presents a finished ornamental appearance.

While a specific embodiment of the invention is illustrated in the drawings, it will of course be understood that changes and obvious modifications may be made in the particular construction shown, and the invention embodied in other forms, as will appeal to those skilled in the art and falling within the scope of the appended claims, without departing from the spirit of the invention.

Subject matter shown and described herein but not claimed, is claimed in our copending application Serial No. 727,795.

What I claim is:

1. In a dispensing device, a supporting member or holder provided with a socket part adapted to receive and hold tube like containers of either circular or square cross sectional form, said socket part having side wall portions to fit against the curved side wall of tube like containers of circular cross sectional form and against the flat side walls of containers of square cross sectional form at different points thereabout to firmly hold the same in position relatively to the supporting member.

2. In a dispensing device, a supporting member or holder provided with a socket part adapted to receive and hold tube like containers of either circular or square cross sectional form, said socket part comprising wall portions with similar transversely curved inner faces disposed at diametrically opposite points about and extending in a common circle to fit a container of circular cross section, and said wall portions being spaced apart circumferentially to accommodate between the same corner portions of a container of square cross section, and right angular shaped wall portions located intermediate the first mentioned wall portions and extending exteriorly of the circle of the curved faces thereof to fit a container of square cross section.

3. In a dispensing device, a supporting member or holder provided with a socket part adapted to accommodate container tubes of either circular or square cross sectional form, said socket at its interior being of general square shape formation, with right angular shaped corner face portions to fit a container tube of square cross section, and having similar transversely curved face portions between said corner portions to fit a container tube of circular cross section.

4. In a dispensing device, a supporting member or holder provided with a socket part adapted to receive and hold tube like contain-

ers of either circular or angular cross sectional form, said socket part comprising wall portions with similar transversely curved inner faces disposed about and extending in a common circle to fit a container tube of circular cross section, and angular shaped wall portions located intermediate the first mentioned wall portions and extending exteriorly of the circle of the curved faces thereof, said angularly shaped wall portions being adapted to fit over and to support between the same a container tube of angular cross sectional form.

5. In a dispensing device, a supporting member or holder provided with a socket part adapted to receive and hold tube like containers of either circular or angular cross sectional form, said socket part comprising wall portions with similar transversely curved inner faces disposed about and extending in a common circle to fit a container tube of circular cross section, and angular shaped wall portions continuous with and located intermediate the first mentioned wall portions and extending exteriorly of the circle of the curved faces thereof, said angularly shaped wall portions being adapted to fit over and to support between the same a container tube of angular cross sectional form.

20 6. In a dispensing device, a supporting member or holder provided with a socket part adapted to receive and hold tube like containers of either circular or angular cross sectional form, said socket part comprising wall portions with similar transversely curved inner faces disposed about and extending in a common circle to fit a container tube of circular cross section, and wall portions located intermediate the first mentioned wall portions and extending exteriorly of the circle of the curved faces thereof, said wall portions being adapted to fit over and to support between the same a container tube of angular cross sectional form.

25 7. In a dispensing device, a supporting member or holder provided with a socket part adapted to accommodate tube like containers of either circular or square cross sectional form, said socket part comprising wall portions with similar transversely curved inner faces disposed in spaced relation at different points about and extending in a common circle to fit a container of circular cross section, and angularly related wall portions located intermediate the first mentioned wall portions to fit over and support between the same a container of square cross sectional form.

30 8. In a dispensing device, an interiorly open supporting member or holder through which articles may pass in dispensing the same, the supporting member including means to hold an open ended container of either round or square cross-sectional form to permit articles to pass therefrom through the support.

9. In a dispensing device, an interiorly open supporting member or holder through which articles may pass in dispensing the same, the supporting member or holder including means to hold an open ended container of either round or square cross-sectional form to permit articles to pass therefrom through the support, said means comprising walls to receive a container of circular cross-section, and said walls being disposed in separated relation to leave spaces to accommodate angular corners of a container of square cross-sectional form.

70 10. In a dispensing device, an interiorly open supporting member or holder through which articles may pass in dispensing the same, the supporting member including means to hold an open ended container of either round or square cross-sectional form to permit articles to pass therefrom through the support, said means comprising wall portions with similar transversely curved inner faces disposed at different points about and extending in a common circle to fit a container of circular cross-section, and said wall portions being spaced apart circumferentially to accommodate between the same corner portions of a container of square cross-section.

80 11. In a dispensing device, an interiorly open supporting member or holder through which articles may pass in dispensing the same, the supporting member or holder including means to hold an open ended container of either round or square cross-sectional form to permit articles to pass therefrom through the support, said means comprising four wall portions with similarly transversely curved inner faces disposed about and extending in a common circle to fit a container of circular cross-section, and said wall portions being of a width and located at equally spaced points about the circle to accommodate between the same corner portions of a container of square cross-section.

90 12. In a dispensing device, an interiorly open supporting member or holder through which articles may pass in dispensing the same, the supporting member including means to hold an open ended container of either round or angular cross-sectional form to permit articles to pass therefrom through the support, said means comprising wall portions having similarly transversely curved inner faces disposed about and extending in a common circle to fit a container of circular cross-section, and said wall portions being spaced apart circumferentially to accommodate between the same the corner portions of a container of angular cross-section.

100 In testimony whereof I hereunto affix my signature.

HUGH MOORE.
